UNITED STATES PATENT OFFICE.

PIETRO CROSTI, OF MILAN, ITALY.

STEAM-LOCOMOTIVE.

1,236,679.

Specification of Letters Patent. Patented Aug. 14, 1917.

Original application filed October 20, 1913, Serial No. 796,254. Divided and this application filed November 30, 1915. Serial No. 64,261.

To all whom it may concern:

Be it known that I, PIETRO CROSTI, a subject of the King of Italy, residing at Milan, Italy, have invented certain new and useful

5 Improvements in Steam-Locomotives, of which the following is a specification.

This invention relates to steam locomotives, and it proposes certain hereinafter-described improvements in the construction 10 and arrangement of the propelling or traction mechanism therefor, whereby great regularity of motion, together with reduced wear upon the parts of the aforesaid mechanism, are obtained.

15 An embodiment of the invention is illustrated in the accompanying drawing, in which:—

Figure 1 is a general side elevation of the improved locomotive.

20 Fig. 2 is a plan view.

Fig. 3 is an enlarged longitudinal section.

According to the present invention, and as represented in said drawing, there is employed at each end of the locomotive, to effect its propulsion, a group of driving cylinders 1, both groups consisting of the same number of cylinders, two in the construction represented. These groups are arranged symmetrically with respect to the 25 geometrical axis of the locomotive, as will be understood from Fig. 2; the piston rods of the cylinders of one group being disposed in longitudinal alinement with those of the other group, and the rods of both groups 30 being disposed nearly in a single horizontal plane, so that the forces acting on said groups of rods will be exerted in nearly-horizontal directions.

The driving truck is arranged centrally 40 of the locomotive, and the axles 2 of its front and rear pairs of driving wheels have their cranks so positioned with relation to each other as to neutralize or counterbalance the effect of the alternate action of the two 45 groups of cylinders, with which latter they are connected by suitable gearing, (shown in dotted lines in Fig. 1). The said truck is articulated to the rigid frame of the locomotive, and where two of such trucks are 50 employed, both of them are articulated to said frame, but are independent of each other.

The boiler is preferably of the type shown and described in my prior application, Serial 55 No. 796,254, filed October 20, 1913, of which

this case is a division, and consists of a pair of cylindrical metallic shells 16, which are arranged horizontally in endwise alinement and above and parallel with the geometrical axis of the locomotive, their confronting 60 inner ends being fixed to the end walls of the enlarged central portion or drum 5 of the boiler. The drum is double-walled, and its inner walls 4 form tube-plates, to which are secured the inner ends of the bundles of 65 tubes 15, disposed within the cylinders 16, the outer ends of the tubes being secured to tube-plates 3, disposed adjacent to the two funnels. Said drum contains the fire-box 6, which is thus common to both cylinders 16, 70 the end walls of the fire-box being constituted by the afore-mentioned tube-plates 4.

The symmetrical construction and arrangement of the boiler, as above described, as well as the symmetrical arrangement of 75 the groups of driving cylinders, with relation to each other and to the geometrical axis of the locomotive, require that the locomotive, whether stationary or in motion, may be easily reached and worked at any point by 80 the engineer or other person or persons in charge, in order to permit it to be driven in both directions. Therefore, to enable the engineer to take his place at the proper end of the locomotive, irrespective of its direction of travel, and, at the same time, to have ready access to all of the working parts, while still maintaining constant communication with the tender and cars, a continuous 85 or uninterrupted passageway or corridor 38 90 is provided, which extends entirely around the boiler and is located between the latter and the outer wall 39 of the locomotive, said wall completely inclosing it, as will be understood from Fig. 2. Along wall 39 are 95 positioned symmetrically and with respect to the geometrical axis of the locomotive, the fuel-boxes 40, and the end and side doors 41 and 44, the doors 41 being located in juxtaposition to the two hand wheels or other 100 controlling devices 42, which latter are designed to govern the operation of the two groups of driving cylinders, and are themselves interconnected so that each of them can control the locomotive as a whole. The 105 floor of the passageway is further provided with doors 43, to permit inspection of the driving gearing, and the wall 39 is provided with suitably-located windows 45.

In the case of a tank-locomotive, the water 110

tanks will be distributed symmetrically there-around, with respect to its geometrical axis, the tanks communicating with each other.

From the foregoing, it will be observed that the arrangement of all parts of the locomotive is symmetrical with respect to its geometrical axis, so that the weight is distributed in a most even manner around the locomotive, and the center of gravity of the latter is maintained upon its aforesaid axis. Also, and more particularly, it is to be noted that a nicely-adjusted counterbalancing action of the two groups of driving cylinders is obtained, in consequence of which, even running is insured, as well as attendant decrease in wear, such wear as does occur being likewise evenly distributed.

I claim as my invention:—

A double-ended steam locomotive having a central driving truck; a group of horizontal driving cylinders at each end connected with the adjacent axle of said truck, each group containing the same number of cylinders,

and the cylinders of each group being arranged parallel with, and symmetrically with relation to, the longitudinal axis of the locomotive; and a pair of devices for controlling the operation of said groups of driving cylinders; the piston rods of the cylinders of one group being disposed in longitudinal alignment with those of the other group, and both groups of rods being disposed nearly in a single horizontal plane, so that the forces acting on said groups of rods will be exerted in nearly-horizontal directions; the cranks of the axles of said driving truck being so positioned with respect to each other as to counterbalance the effect of the alternate action of said groups.

In testimony whereof I have affixed my signature in presence of two witnesses.

PIETRO CROSTI.
